CLAIM

The ornamental design for a solar garden decoration light, as shown and described.

DESCRIPTION

FIG. 1 is a front elevational view a solar garden decoration light showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof; and,

FIG. 7 is perspective view thereof.

The broken lines show portions of the solar garden decoration light that form no part of the claimed design.
